UNITED STATES PATENT OFFICE.

JOHN W. LANG, OF REDONDO BEACH, CALIFORNIA.

CHAIR.

1,349,164.

Specification of Letters Patent. Patented Aug. 10, 1920.

Application filed October 18, 1919. Serial No. 330,393.

To all whom it may concern:

Be it known that I, JOHN W. LANG, a citizen of the United States, residing at Redondo Beach, in the county of Los Angeles and State of California, have invented new and useful Improvements in Chairs, of which the following is a specification.

My object is to make a chair which may be readily transformed into a table, and 10 my invention consists of the novel features herein shown, described and claimed.

Figure 1 is a perspective of a chair transformable into a table in accordance with the principles of my invention.

15 Fig. 2 is a side elevation of the stand and chair seat with the back and table construction removed.

Fig. 3 is an edge view of the chair back and table construction removed from the 20 stand.

Fig. 4 is a perspective showing the chair back tilted forwardly upon the stand in solid lines and showing the movement of the chair back upon the stand in dotted lines, 25 and showing the leaves unfolded to make a round table in dotted lines.

Fig. 5 is a view analogous to Fig. 4 and showing the leaves unfolded and dropped to make a small table.

30 Fig. 6 is a top plan view upon an enlarged scale and showing the table extended.

Fig. 7 is a sectional side elevation upon an enlarged scale with the parts in position to form a chair.

35 Fig. 8 is a fragmentary detail showing the connection between the stand and the chair back with the parts shown in full lines in the position forming a table and in dotted lines in the position forming a chair.

40 Fig. 9 is a sectional detail showing the disappearing hinge, the view being taken on the line 9—9 of Fig. 5 and showing the leaves unfolded.

Fig. 10 is a view analogous to Fig. 9 and 45 showing the leaves folded.

Fig. 11 is a fragmentary top plan view of the stand.

The details of the stand 1 are shown in Figs. 1, 2, 4 and 5. The lower side bars 2 and 3 are mounted upon casters 4 and 5 and are rigidly connected by a cross-piece 6. The rear posts 7 and 8 extend upwardly from the rear ends of the side bars 2 and 3 and the front posts 9 and 10 extend upwardly from the forward ends of the side bars 2 and 3. The seat frame 11 rigidly

connects the posts 7, 8, 9 and 10 about half way up from their bottoms, the lower ends of the posts 7, 8, 9 and 10 serving as legs for the chair and the upper ends of the posts 60 serving as supports for the chair arms. The chair arms 12 and 13 are rigidly mounted upon the upper ends of the posts 9 and 7 and 10 and 8. The chair arms 12 and 13 have flat straight horizontal upper faces 65 14 and 15 and straight parallel vertical inner faces 16 and 17. Pivot plates 18 and 19 are recessed into the faces 16 and 17 at their rear ends and the pivot pins 20 and 21 extend inwardly from the plates 18 and 70 19. Retaining pins 22 and 23 are fixed in the arms 12 and 13 and extend inwardly near the forward ends of the arms. Rubbing heads 24 and 25 are fixed to the arms 12 and 13 to project slightly beyond the 75 faces 16 and 17 directly above the retaining pins 20 and 21. The seat 26 is removably mounted in the seat frame 11.

The details of the chair back and table construction 27 are shown in Figs. 1, 3, 4, 5, 7, 80 8, 9 and 10.

The chair back frame consists of the side bars 28 and 29, the lower cross bar 30, the upper cross bar 31 and the panel 32 inserted between the side bars and cross bars. The 85 side bars 28 and 29 have straight outer faces 33 and 34 fitting between the faces 16 and 17. Plates 35 and 36 are embedded into the faces 33 and 34 and have longitudinal slots 37 extending some distance and cross 90 slots 38 leading laterally to the longitudinal slots 37, the cross slots 38 being slightly above the centers of the longitudinal slots 37.

The pivot pins 20 and 21 pass through the cross slots 38 into the longitudinal slots 37 95 and when the chair back is elevated to a vertical position and lowered bodily the pins 20 and 21 pass to the upper ends 39 of the slots 37, and when the back is tilted forwardly and moved forwardly to be centered 100 over the stand 1 the pins 20 and 21 pass to the lower ends 40 of the slots 37. When the chair back and table construction 27 is in a vertical position the chair back and table construction may be removed bodily from the stand 1 by lifting it until the pins 20 and 21 will pass outwardly through the slots 38. The slots 38 extend forwardly when the parts are in a vertical position and extend downwardly when the parts are in a 110 horizontal position.

Plates 41 and 42 are embedded into the

faces 33 and 34 and have L-shaped slots 43 opening forwardly in a vertical position and downwardly in a horizontal position, so that when the chair back and table construction 5 27 is tilted forwardly the plates 41 and 42 will pass downwardly between the rubbing heads 24 and 25 and slide forwardly on the pins 22 and 23 until the pins enter the slots 43, and then a slight backward movement 10 15 will lock the parts in a horizontal position. The heads 24 and 25 and the plates 41 and 42 serve to protect the wood. The cross bar 30 passes between the posts 7 and 8 directly above the seat 26.

15 Arms 44 extend downwardly from the side bars 28 and 29 and a cross bar 45 connects the lower ends of the arms 44. The arms 44 engage the seat frame 11 and form stops to hold the chair back and table construction 20 upright.

The side bars 28 and 29 are slightly tapered in side elevation and the panel 32 is slightly inclined. Frame boards 46 are secured to the back of the cross bar 30 and 25 fit against the lower edge of the cross bar 31 so as to bring the boards 46 practically straight up and down. A spacing board 47 is secured to the back side of the cross bar 45, and a similar spacing board 48 is 30 secured against the back side of the cross bar 31.

The rigid sliding table top leaves 49 and 50 fit against the back sides of the boards 47 and 48 when the table top is contracted.

35 The slides 51 and 52 are fixed against the bottom of the leaf 49 and the slides 53 and 54 are fixed against the bottom of the leaf 50, said slides 53 and 54 being offset relative to the slides 51 and 52 so that the slides 51 and 53 will pass along side of each other and the slides 52 and 54 will pass along side of each other when the table is contracted. T-slots 55, 56, 57 and 58 are formed in the slides 51, 52, 53 and 54.

40 45 Screws 59, 60, 61 and 62 are inserted downwardly through the T-slots 55, 56, 57 and 58 and screwed rigidly into the board 46, said screws fitting loose enough in the slots to allow the slides 51, 52, 53 and 54 to move, 50 and the slots being long enough to allow the leaves 49 and 50 to move together as in Fig. 5 and to allow the leaves 49 and 50 to move apart for the insertion of the extension leaves 63 and 64.

55 Filler blocks 65 are inserted against the back sides of the side bars 28 and 29 to a level with the back face of the board 46 and form slideways for the slides 51, 52, 53 and 54. A brace 66 connects the center ones 60 of the filler blocks 65 and passes back of the board 46 to stiffen the board.

The folding leaf supporting slides 67 and 68 have T-slots 69 and 70 and the slides 67 and 68 fit upwardly against the sliding 65 leaves 49 and 50 and screws 71 and 72 are

inserted upwardly through the slots 69 and 70 and screwed rigidly into the leaves 49 and 50. The slides 67 and 68 are longer than the widths of the leaves 49 and 50 together, so that when the leaves 49 and 50 are together the ends 73, 74, 75 and 76 of the slides 67 and 68 extend beyond the side edges of the leaves 49 and 50 and these ends are directly back of the rear ends of the arms 12 and 13. Spacing blocks 77 and 78 are 75 fixed against the lower sides of the leaves 49 and 50 so as to bear against the inner sides of the slides 67 and 68 and hold the slides straight.

Intermediate folding leaves 79 and 80 80 are connected to the outer edges of the sliding leaves 49 and 50 by invisible hinges 81. Referring to Figs. 9 and 10 the hinges 81 are recessed into the meeting edges, so that when the intermediate folding leaves 79 and 80 85 swing outwardly and downwardly the leaves will be supported by the ends of the slides 67 and 68 and the upper face 82 of the table will be perfectly smooth, and so that when the leaves 79 and 80 swing upwardly, inwardly and downwardly they will lie flat upon the leaves 49 and 50.

The outer folding leaves 83 and 84 are connected to the outer edges of the intermediate folding leaves 79 and 80 by butt 95 hinges 85 secured to their lower faces, so that when the leaves 79 and 80 are supported by the slides 67 and 68 the leaves 83 and 84 will hang downwardly as in Fig. 5, and so that when the leaves 83 and 84 are raised 100 until their inner edges engage the outer edges of the leaves 79 and 80 stiff joints will be formed and continued upward movement will carry the leaves 79 and 80 over on to the leaves 49 and 50. The slides 67 and 68 105 may be pulled outwardly to support the leaves 83 and 84.

When the table is contracted and folded, as in Fig. 4, the leaves 83 and 79 lie upon the leaf 49 and the leaves 84 and 80 lie upon the leaf 50. Handwheels 86 and 87 are secured to the lower faces of the leaves 83 and 84 and a hook 88 is secured to one leaf to engage an eye 89 secured to the other leaf to hold the leaves folded while the parts 115 are upright.

Thus I have produced a chair which may be readily transformed into a square table, or a round table, or an extension table.

Various changes may be made without departing from the spirit of my invention as claimed.

I claim:

1. A transformable chair comprising a stand having horizontal parallel arms, pivot 125 pins extending inwardly from the rear ends of the arms, supporting pins extending inwardly from near the front ends of the arms, a chair back having side bars fitting loosely between the arms, plates at the outer faces 130

- of the side bars and having longitudinally extending slots and lateral slots intermediate of the ends of the longitudinally extending slots, said slots being adapted to receive the pivot pins, second plates at the outer sides of the side bars and having L-slots adapted to receive the supporting pins, and a table top mounted upon the chair back.
2. A transformable chair comprising a stand having horizontal parallel arms, pivot pins extending inwardly from the rear ends of the arms, supporting pins extending inwardly from near the front ends of the arms, rubbing heads secured to the arms above the supporting pins, a chair back having side bars fitting loosely between the arms, plates at the outer faces of the side bars and having longitudinally extending slots and lateral slots intermediate of the ends of the longitudinally extending slots, said slots being adapted to receive the pivot pins, second plates at the outer sides of the side bars and having L-slots adapted to receive the supporting pins, and a table top mounted upon the chair back.
3. A transformable chair comprising a

stand having horizontal parallel arms, a chair back pivotally mounted between the rear ends of the arms and adapted to tilt forwardly and be supported in a horizontal position, leaves secured to the chair back, intermediate leaves secured to the first leaves by invisible hinges, means for supporting the intermediate leaves in their unfolded positions, and outer drop leaves secured to the intermediate leaves by butt hinges.

4. A transformable chair comprising a stand, a chair back pivotally connected to the stand and adapted to swing from a vertical position to a horizontal position, means for supporting the chair back in the horizontal position, leaves slidably mounted upon the chair back, extension leaves adapted to be inserted between the sliding leaves, intermediate leaves connected to the outer edges of the sliding leaves by invisible hinges, and outer leaves connected to the intermediate leaves by butt hinges.

In testimony whereof I have signed my name to this specification.

JOHN W. LANG.
